[57] CLAIM

The ornamental design for a scuba tank holder, as
shown and described.

DESCRIPTION

FIG. 1 is a left side, top and front perspective view of a
scuba tank holder showing my new design;

FIG. 2 is a front elevational view thereof, with two
tanks shown in environmental association with the two
tanks in banded relationship;

FIG. 3 is a top plan view thereof;

FIG. 4 is a rear elevational view thereof;

FIG. 5 is a side elevational view thereof, and the side
opposite being a mirror image.

The broken line showing of two tanks and support band
is for illustrative purposes only and forms no part of the
claimed design.
